MAIL BOX

George J. Overmyer, Tulsa, Okla.

Application August 5, 1943, Serial No. 497,485

1 Claim. (Cl. 232—45)

This invention relates to mail boxes, one of the objects being to provide a box so constructed that it can be made entirely of glass or other plastic material.

A further object is to utilize a self-closing plastic plate or closure for the box which is held against unintentional removal because of its peculiar relationship to the wall or other supporting structure to which the mail box is connected.

A further object is to provide a top closure which, on arriving in closed position, will become interlocked with the top of the box in such a manner as to prevent seepage of moisture into the box through the top thereof.

Another object is to provide a closure which can be opened readily by hand and, if desired, can be given an initial impulse when released so as to start it automatically toward its closed position.

Another object is to form the mail box of a transparent material whereby the contents of the box can be seen at a distance when viewed at any angle.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawings the preferred form of the invention has been shown.

In said drawings

Figure 1 is a front elevation of a mail box embodying the present improvements.

Figure 2 is a side elevation thereof.

Figure 3 is a top plan view.

Figure 4 is a central vertical section taken from front to rear, the attaching clips being shown in elevation.

Figure 5 is a side elevation of the top portion of the mail box showing the closure pushed back to open position.

Figure 6 is a section on line 6—6, Figure 4, taken through one side portion of the box.

Figure 7 is a section on line 7—7, Figure 4, taken through one side portion of the box.

Figure 8 is a side elevation of the bottom portion of the box showing a slightly modified construction.

Figure 9 is a side elevation of the bottom portion of the box and showing the lower clamp utilized not only as a support for magazines and

other large parcels of mail, but also for use as a hasp for locking the bottom closure in set position.

Figure 10 is a side elevation of the bottom portion of the mail box with a modified form of clip and paper or parcel holder.

Figure 11 is a side elevation of a portion of a modified form of mail box.

At the outset it is desired to point out particularly the fact that the present mail box and its closures are made entirely of transparent material such as glass, plastic or the like, the purpose being to provide a structure the contents of which can be seen at a distance when viewed at any angle. This is especially important in localities where the box must be located at a point removed from the normal location of the user and under such conditions the box, if made partly or entirely of opaque material such as sheet metal or the like, would frequently obscure from the observer small articles of mail contained in the box.

The box can be of any shape desired but, in the structure illustrated, the body portion 1 has its back wall offset into the body as at 2 to provide a clearance 3 into which magazines and other large articles of mail can be thrust after the box has been attached to a wall, post or other supporting structure indicated generally at S. The box has a depression 4 in the back portion of the top thereof designed to receive the lower end of a clip 6 which can be a bow spring formed of a suitable material and fastened at its center to the supporting structure S by a screw 7 or the like. This leaves the upper end 8 of the spring extending well above the top of the box for the purpose hereinafter explained. The back surface of the bottom of the box is adapted to bear, as at 9, against the supporting structure S and is recessed at the center, as shown at 10 to receive one end portion of a clip 11 likewise formed preferably of a resilient material of sufficient strength to hold said portion of the box clamped tightly against the supporting structure. This strip of material forming the clip is attached to structure S by a screw 12 or the like and, in the form of the device illustrated in Figs. 1 to 4 inclusive, is extended downwardly and forwardly to provide a tongue 13 the free end of which is upturned as at 14 to constitute a stop.

The top of the box 1 is inclined downwardly and forwardly as indicated at 15 and is provided with a mail-receiving slot 16 provided at each side with an upwardly extended side wall 17 inclined downwardly and forwardly and formed

with a groove 18 in its outer side terminating at its lower end in a depression 19 and a stop shoulder 20. Another flange 21 is extended along the back portion of the slot 16 and has a longitudinal groove 22 in its rear surface which, if desired, can be filled with a cushioning strip 23 of felt or the like although this cushioning strip may be eliminated if desired. A lip or rib 24 extends upwardly from the front portion of the slot 16 and is preferably rounded as shown. The upper portion of the lip 24 and of the flanges 17 and 21 are all located in an inclined plane preferably parallel with the plane occupied by that portion of the top 15 located back of the flange 21. Said portion has been shown at 25. The front portion 26 of the top 15 is preferably pitched at a greater angle than the rear portion 25 and extends from the base of the lip or bead 24 forwardly to a rib 27 into which it merges and which projects forwardly beyond the front surface of the body 1 of the mail box.

The top closure consists of a plate 28 formed of glass or other suitable plastic material, this plate being provided at its sides with flanges 29 lapping the outer surfaces of the flanges 17. As shown particularly in Fig. 6 the flanges 29 have inwardly extended longitudinal beads or ribs 30 which project into the respective grooves 18 and, as will be seen by referring to Fig. 5, the forward ends of these beads are provided with downwardly extended rounded nodes or lugs 31. The ribs 30 do not fit snugly in the grooves 18 but are of a thickness somewhat less than the height of the grooves. Thus it is possible for the plate 28 to have a limited swinging movement upwardly or downwardly relative to the top surfaces of the flanges 17 and 21 and the lip or rib 24. This movement is just sufficient to allow a lip 32 extending across the forward portion of the plate 28 to ride over the rib 24 after which the nodes or lugs 31 will gravitate into the recesses 19 and allow the forward edge portion of the plate to drop on the surface 26 so as to lap the rib 24 and form a seal against seepage of moisture into the slot 16. When the plate is thus located, a depending flange 33 carried by the plate and interposed between the rear end portions of the flanges 29, will be in contact with the cushioning material 23 or with the flange 22 if the cushioning material is not used.

Another construction to seal the top opening against seepage of moisture into the slot 16 can also be utilized. In such a modified form the lip 32 is eliminated and an extension 28' of the plate 28 rests down on the flat top 24' of the rib 24'. This modified form is illustrated in Fig. 11 to show the extension 28' of the plate 28 without a lip 32.

A projection 34 extends upwardly from the plate 28 and by pressing backwardly thereon the nodes 31 will ride upwardly out of the recesses 19, thereby lifting the lip 32 over the rib or lip 24. This action is permitted because of the play between the ribs 30 and the upper walls of the grooves 18. Continued back pressure against the projection 34 will result in forcing the back end of the closure against the upper end portion of the resilient clip 6 which thus will be placed under tension. At this time the slot 16 will be exposed and an article of mail can be dropped therethrough into the box. As soon as the closure 28 is released, the tensioned end portion 8 of the clip 6 will impart an initial forward impulse to the closure which thereafter will slide by gravity back to its normal or closed position

as shown in Figs. 2, 3 and 4. The open position of the closure has been illustrated in Fig. 5.

The bottom of the body 1 is inclined upwardly and forwardly and is open, the outlet 35 preferably being larger than the interior of the body so that mail can slide freely from the body when open at the bottom without danger of clogging. A transverse groove 36 is formed in the front surface of the bottom portion of the body and communicates, at its ends, with corresponding grooves 37 in the sides of the body, these latter grooves being inclined downwardly and backwardly so as to be parallel with the inclined bottom of said body. The rear or lower ends of the side grooves 37 terminate at stop shoulders 38.

The bottom closure comprises a plate 39 having a transverse flange 40 extending upwardly from its forward edge and provided with a backwardly extended rib 41. When the closure is shut, this rib is adapted to project into the front groove 36 and, if a cushioning material 42 is located in this groove, the rib 41 will contact therewith. The plate has side flanges 43 which, as illustrated in Fig. 7, extend into the respective grooves 37 so as thus to support the plate close to the inclined bottom of body 1. A projection 44 extends downwardly from the forward portion of the plate and constitutes a finger piece by means of which the bottom closure can be slid upwardly and forwardly for the purpose of opening the bottom of the box. This sliding movement can be limited by one or more plugs 45 of felt or other cushioning material inserted through the plate and projecting upwardly therefrom so that the plugs can come against the front wall of the bottom opening of the body when the closure is moved to full open position.

Obviously when the bottom closure is released after being slid upwardly, it can gravitate to closed position.

Instead of relying upon the plugs 45 for limiting the forward sliding movement of the bottom closure 39, a modified construction such as illustrated in Fig. 8 can be used. In this device the bottom closure 39' with the finger piece 44' extending therefrom has upwardly extending ears 46 adjacent to the back ends of the side flanges 43' and these ears work between the stop shoulders 38 and supplemental stop shoulders 47 which are located on the body 1 above but adjacent to the forward ends of the grooves 37. Consequently when the closure 39' is pulled forwardly and upwardly the ears 46 will come against stop shoulders 47 to limit such movement whereas, when the closure is released, it will gravitate back to the position shown in Fig. 8, such movement being limited by the shoulders 38.

When the bottom closures are in their full open positions, their forward or projecting ends will sag under their own weight because of the play between the flanges 43 and the grooves 37 in which they are located. Thus the bottom closures will not shut until their forward ends are lifted slightly whereupon they will slide backwardly and downwardly as already explained.

Instead of utilizing an elongated tongue such as shown at 13 and 14 to be employed solely for the purpose of deflecting articles of mail released from the body of the box, said tongue can be formed with a slot 48. The bottom closure 39, which can be of the construction shown in Figs. 1 to 4 or of the construction shown in Fig. 8, has an integral elongated ear 50 extending downwardly therefrom and formed with an opening 51. This ear is so located that when the slotted

tongue 52 is swung upwardly toward the bottom closure from the normal position indicated by broken lines in Figure 9, it can be caused to embrace ear 50 after which a padlock 53 or the like can be inserted in the opening 51. This will of course lock the bottom closure in shut position so that mail cannot be removed until after the padlock has been removed and the tongue 52, constituting a hasp, has been allowed to spring downwardly to its normal position.

A further modification has been illustrated in Fig. 10 wherein the tongue 54 of the bottom attaching clip has a supplemental finger 59 extending downwardly and backwardly therefrom so as to form, with the tongue 54, a V-shaped means for holding magazines or the like thrust against the supporting surface S.

The primary purpose of the tongues 13, 52 and 54 is to prevent released mail from falling straight down from the mail box when the bottom closure is open. Instead this released mail will be intercepted and deflected forwardly to a point where it can be reached conveniently.

It will be obvious from the foregoing that a box constructed as herein described will afford complete protection for its contents against rain, swirling snow, etc., inasmuch as the closures will shut automatically when released and, when shut, will be so positioned as to prevent seepage of moisture past them and into the box. This is important where boxes are exposed to the weather because it frequently happens with ordinary types used, that one or both of the closures are left open and moisture thus enters the box and causes it to deteriorate. By making all of the box out of non-corrosive material such as glass, plastic or the like, there is no danger of deterioration because of climatic conditions and, by mounting the closures as described, the contents of the box are always fully protected.

It will be noted that after the box has once been mounted, it becomes impossible to unintentionally separate the closures from the body. The top closure cannot be pushed back far enough to disengage it from the flanges 17 unless its rear edge is lifted to near vertical after being pushed back against the supporting surface.

It is to be understood that the term "plastic" employed in the claim is used to designate glass or any other molded material of a similar nature.

What is claimed is:

The combination with a mail box having an end inclined downwardly from back to front and provided with an opening, and guide grooves in the sides of the box adjacent to and parallel with said end, each of said grooves being open at its upper or back end and having a bottom wall provided at its lower end with a depression, of an inclined closure straddling said box end and 15 slidable by gravity to low or closed position across the opening, the upper or back end of the inclined closure being supported by and in slidable engagement with said inclined end of the box, nodes on the sides of the closure supported by 20 and in sliding engagement with the bottom walls of the grooves, said nodes being positioned and proportioned to drop into the depressions and deposit the closure flat upon the open end of the box when the closure is in its extreme low or 25 closed position, means on the closure and slidable in the grooves for holding the closure and box assembled, said means being insertible into the open upper ends of the grooves, and means at the front or lower end of the closure positioned 30 for overlying engagement with a portion of the front or lower end of the box top when the closure is in its extreme low or closed position with the nodes in the depressions.
